CLAIM

The ornamental design for a wearable device as shown and described.

DESCRIPTION

FIG. 1 is a front view of a wearable device showing the claimed design;

FIG. 2 is a rear view thereof;

FIG. 3 is a right side view thereof;

FIG. 4 is a left side view thereof;

FIG. 5 is a top view thereof; and,

FIG. 6 is a bottom view thereof.

The broken lines in the figures show portions of the wearable device that form no part of the claimed design.

The Figures are illustrated to show contrasting appearance. Areas of the wearable device that appear in different shades of gray represent areas with contrasting appearances.

FIG. 1

FIG. 2

FIG. 3

FIG. 4

FIG. 5

FIG. 6
